US00D857910S

(12) **United States Design Patent** (10) **Patent No.:** **US D857,910 S**
(45) **Date of Patent:** **** Aug. 27, 2019**

(54) **TRANSCUTANEOUS ELECTRICAL NERVE STIMULATION DEVICE**

(71) Applicant: **Neurometrix, Inc.**, Waltham, MA (US)

(72) Inventors: **Marc Cryan**, Maynard, MA (US);
Bonniejean Boettcher, Maynard, MA (US); **Elizabeth P. Goodrich**, Roslindale, MA (US); **Evan Williams**, Boston, MA (US); **Gregory Scott Torrisi**, Midlothian, VA (US); **Martin Jacob**, Belmont, CA (US)

(73) Assignee: **Neurometrix, Inc.**, Waltham, MA (US)

(**) Term: **15 Years**

(21) Appl. No.: **29/618,435**

(22) Filed: **Sep. 21, 2017**

(51) LOC (12) Cl. **28-03**

(52) U.S. Cl.

(57) **CLAIM**

The ornamental design for a transcutaneous electrical nerve stimulation device, as shown and described.

DESCRIPTION

FIG. 1 is a front perspective view of the transcutaneous electrical nerve stimulation device, showing our new design; FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.
